UNITED STATES PATENT OFFICE.

VICTOR GOLDBERGER, OF CLEVELAND, OHIO.

CIGAR-TIP.

1,217,590.

Specification of Letters Patent. Patented Feb. 27, 1917.

Application filed March 21, 1916. Serial No. 85,560.

To all whom it may concern:

Be it known that I, VICTOR GOLDBERGER, a citizen of the United States, residing at Cleveland, in the county of Cuyahoga and State of Ohio, have invented certain new and useful Improvements in Cigar-Tips, of which the following is a specification.

My invention relates to improvements in cigar tips, the primary object of the invention being to provide a generally improved cigar tip through the medium of an improved reinforced and anchored tubular stem or tip insert, the latter being preferably formed of a single or suitable length of tough resilient material, such as a goose quill, or the like, of suitable length, such tubular stem or insert being provided with a suitable reinforcing beading at the mouth and extending flush with the tip portion of the cigar, thereby eliminating the necessity of first cutting the tip off of the cigar in the usual manner preparatory to smoking, and not only improving the draft and smoking qualities of the cigar but also reinforcing and improving the tip of the same, as well as generally improving the cigar as a whole, and resulting in considerable economy both in the manufacture and in the use.

30 The improved tubular stem or insert is preferably applied or embodied in the tip portion of the cigar during the process of its manufacture and is provided with suitable anchoring and tip protecting means as will hereinafter more fully appear.

With the above mentioned and other ends in view, the invention consists in the novel construction, combination, and arrangement of parts, hereinafter described, illustrated 40 in some of its embodiments in the accompanying drawings, and particularly pointed out in the appended claims.

Referring to the drawings forming a part of this specification, Figure 1 is a side elevation of a cigar having its tip portion equipped with the tubular reinforcing insert constructed and mounted in accordance with my invention.

Fig. 2, an end view of the tip portion 50 thereof.

Fig. 3, a detail view of the tubular insert, removed.

Fig. 4, a longitudinal sectional view of the same.

Fig. 5, a view of a modified form of same. 55

Fig. 6, a view of a further modified form of same.

Fig. 7, a view of a still further modified form of same.

Similar numerals of reference designate 60 like parts throughout all the figures of the drawings.

The cigar 1 may be of any suitable and convenient form and the improved tubular stem or insert is preferably inserted or embodied in the tip portion 1^a thereof during the process of forming or manufacturing 65 the cigar.

The improved stem or insert 2 is preferably formed of tough resilient material, 70 such as a suitable length of goose quill, such material having been found to be admirably adapted for this purpose and such tubular stem or insert is preferably reinforced and anchored within the tip portion 75 1^a of the cigar by having its marginal edges at one end outwardly curved and flattened with the raw edges spaced inwardly forming a flattened marginal tip beading 2^a, the folded or bent over portion of the latter 80 extending flush with and said raw edges being covered and protected by the tip portion of the cigar, said tip beading 2^a not only serving to protect the tongue of the user but also serving to protect and reinforce the extreme tip portion of the cigar. 85

The tip beading 2^a also serves to reinforce the marginal or tip portion of the stem 2, and serves further to anchor the stem or insert 2 as against inward longitudinal 90 movement within the cigar tip.

As a further means of anchoring the tubular stem or insert 2 within the tip portion of the cigar the inner or opposite end of the stem 2 may be provided with suitable 95 anchoring means, such, for example, as the inner or anchor beading 2^b, shown in Fig. 5 of the drawings, and formed in a manner similar to that shown in Figs. 1, 2 and 4 of the drawings, or if desired, such anchoring means may comprise a plurality of longitudinally extending anchor tongues 2^c as shown in Fig. 6 of the drawings, said anchor tongues 2^c being preferably slightly spaced apart, as shown. A still further form of 100 anchoring means may comprise a plurality or series of anchor openings 2^d, as shown in Fig. 7 of the drawings, such anchor open-

ings, in this instance, also serving as inlet ports communicating with the adjacent parts of the cigar.

The tubular stem or insert 2 is preferably flattened as shown most clearly in Fig. 2 of the drawings.

From the foregoing description, taken in connection with the accompanying drawings, the operation and advantages of my 10 invention will be readily understood.

Having thus described some of the embodiments of my invention, without having attempted to set forth all the forms in which it may be made, or all the modes of its use, 15 what I claim and desire to secure by Letters Patent, is,—

1. In a cigar, the combination with a cigar tip, of a cigar tip reinforcing tube formed

of a goose-quill having one end turned outwardly into a reinforcing flattened tip beading, the raw edge of the latter extending inwardly and being covered and protected by the cigar tip. 20

2. In a cigar, the combination with the tip portion thereof; of a reinforced goose 25 quill stem mounted therein and having an outwardly curled marginal tip beading extending flush therewith and having the raw edge of the tip beading covered by said tip portion of the cigar. 30

In testimony whereof I have affixed my signature in the presence of two witnesses.

VICTOR GOLDBERGER.
